CLAIM

The ornamental design for a pressure bleed-off handle, as shown and described.

DESCRIPTION

FIG. 1 is a perspective view of a pressure bleed-off handle, showing our new design.

FIG. 2 is a front plan view of the pressure bleed-off handle of FIG. 1.

FIG. 3 is a rear plan view thereof.

FIG. 4 is a top plan view thereof.

FIG. 5 is a bottom plan view thereof.

FIG. 6 is a right side elevation view thereof.

FIG. 7 is a left side elevation view thereof; and,

FIG. 8 is a perspective view of the pressure bleed-off handle, and showing a bleed-off clamp in broken lines.

The broken lines in the drawings depict portions of the pressure bleed-off handle that form no part of the claimed designs.

1 Claim, 4 Drawing Sheets
